United States Patent

Des. 239,404
Patented Mar. 30, 1976

239,404

PUSH BUTTON TOY

Michael I. Satten, 245-20 Grand Central Parkway,
Bellrose, N.Y. 11362

Filed Jan. 23, 1975, Ser. No. 543,404

Term of patent 14 years

Int. Cl. D21—01

U.S. Cl. D34—15 LL

FIG. 1

FIG. 2

FIG. 3

FIG. 4

FIG. 5

FIG. 6

FIG. 1 is a front elevational view of a push button toy showing my new design;

FIG. 2 is a top plan view thereof;

FIG. 3 is a left side elevational view thereof;

FIG. 4 is a right side elevational view thereof;

FIG. 5 is a rear elevational view thereof; and

FIG. 6 is a bottom plan view thereof.

I claim:

The ornamental design for a push button toy, as shown.
